Inventor
Cornelius Bradley,

By Clarence A. O'Brien

Attorney

UNITED STATES PATENT OFFICE.

CORNELIUS BRADLEY, OF RYDAL, PENNSYLVANIA.

COW-TAIL HOLDER.

Application filed April 13, 1926. Serial No. 101,742.

This invention relates to a cow tail holder and has for its primary object to improve and simplify articles of this general character.

5 To the attainment of this end, my holder is in the form of a single unit consisting of a pair of metallic strips pivotally interconnected intermediate their ends and so cooperatively constructed at their ends as to provide a leg clasp and a tail clasp at opposite ends of the unit.

10 A further object of the invention resides in the provision of such a single unit wherein the metallic strips are forcibly maintained 15 in such a relationship as to bind the clasps at opposite ends of the unit upon the leg and tail respectively of the animal, the metallic strip being further so cooperatively constructed intermediate their ends as to 20 facilitate the ready opening of the clasps when it is desired to apply or remove the same.

Other objects will become apparent as the 25 nature of the invention is better understood and when taken in connection with the accompanying drawing.

In the accompanying drawing forming a 30 part of this application and in which like numerals designate like parts throughout the views:—

Figure 1 is a top plan view of my improved cow tail holder.

Figure 2 is a side elevation thereof, and

35 Figure 3 is a side elevation of the metallic strips prior to it being bent into proper shape to cooperate with the other properly bent strips to provide the present holder.

Now having particular reference to the drawing, my novel cow tail holder constitutes the provision of a pair of suitable 40 length strips of metal 5—5 that are formed adjacent their forward ends with inwardly struck semi-circular ears 6—6 that are adapted for overlapping relation as shown 45 in Figure 1, in order that said strips may be pivotally interconnected as at 7. The forward ends of the strips are bent into substantially semi-ovular shape to provide jaws 8—8 of a clasp that is adapted for engagement 50 with the hock of a cow's leg.

The metallic strips rearwardly of the ears 6—6 are bent outwardly as at 9—9 to provide handles for facilitating the opening of the jaws of the clasp and thence inwardly 55 as at 10—10, the upper edge of the inwardly bent portion 10 of one strip being notched

as at 11 throughout substantially its entire length while the lower edge of the inwardly bent portion 10 of the other strip is notched as at 12, also throughout substantially its 60 entire length in order that said portions 10—10 will ride over each other during the opening and closing of the jaws 8—8 of said cow leg clasps.

At the extreme inner end of the inwardly 65 bent portions 10—10 of said metallic strips 5—5, the same are bent rearwardly in a horizontal plane for providing jaws 13—13 that are milled on their inner faces for providing a clasp for the cow's tail.

70 The outwardly bent portions 9—9 of the strip are formed with transversely registering openings 14 within which are anchored the ends 15—15 of a helical spring 16, said 75 ends being bent forwardly and in outwardly converging relation as clearly disclosed in Figure 1.

It will thus be seen that I have provided a highly novel, simple, and efficient form of cow tail holder that is well adapted for all 80 the purposes heretofore designated, even though I have herein shown and described the preferred embodiment of the invention, it is nevertheless to be understood that modifications may be had without effecting the 85 spirit and scope of the appended claims.

Having thus described the invention, what I claim as new and desire to secure by Letters Patent is:—

1. In a cow tail holder of the character 90 described, a single unit consisting of a pair of metallic strips pivotally interconnected intermediate their ends and being so cooperatively constructed at their ends as to provide a normally closed animal leg clasps, 95 and an animal tail clasp.

2. In a cow tail holder of the character described, a single unit consisting of a pair of metallic strips pivotally interconnected intermediate their ends and being so cooperatively constructed at their ends as to provide a normally closed animal leg clasps, 100 an animal tail clasp, and means for normally maintaining said clasps in closed position.

3. In a cow tail holder of the character 105 described, a pair of metallic strips pivotally interconnected intermediate their ends, co-operating clasp jaws formed at certain ends of the strips, outwardly converging clasp opening handle members at the opposite 110 sides of the pivotal connection, inwardly converging overlapping portions at the ends

of said handle members, and cooperating jaw plates in the ends of the said inwardly converging portion for providing a tail clasp.

- 5 4. In a cow tail holder of the character described, a pair of metallic strips pivotally interconnected intermediate their ends, co-operating clasp jaws formed at certain ends of the strips, outwardly converging clasp
- 10 opening handle members at the opposite sides of the pivotal connection, inwardly

converging overlapping portions at the ends of said handle members, cooperating jaw plates in the ends of the said inwardly converging portion for providing a tail clasp, ¹⁵ and spring means for normally maintaining the clasp jaws and jaw plates in closed position.

In testimony whereof I affix my signature.

CORNELIUS BRADLEY.
